UNITED STATES PATENT OFFICE.

EDGAR BEVERLEY FENBY, OF COVENTRY, ENGLAND.

FOLDING-MACHINE FOR COLLAR, CUFF, AND LIKE BLANKS.

1,099,594.

Specification of Letters Patent.

Patented June 9, 1914.

Application filed July 11, 1912. Serial No. 708,845.

To all whom it may concern:

Be it known that I, EDGAR BEVERLEY FENBY, subject of the King of Great Britain, residing at Coventry, England, have 5 invented certain new and useful Improvements in Folding-Machines for Collar, Cuff, and like Blanks, of which the following is a specification.

The object of this invention is to render 10 possible a more rapid and accurate operation of the blank folding machines for collars, cuffs and the like in which the moving die presses the blank on to a table where the edges are folded and the folded blank subsequently pressed. The speed of operation, 15 as well as the accuracy in such machines, has been seriously impeded because of the difficulty of rapidly removing the folded blank and properly inserting a fresh one. Difficulties have also been encountered in the 20 adjusting and cleaning of the machine so as to prevent soiling of the blank.

I shall first of all describe the general construction and operation of a folding machine and then proceed to deal with the 25 novel features and improvements according to the present invention.

Referring to the accompanying drawings:—Figure 1, is a side elevation of the 30 machine with the die head raised. Fig. 1^a is a fragmentary view of the operating lever which effects the relative movements of the die-head parts. Fig. 2, is a front elevation of the machine looking in the direction of 35 the arrow X in Fig. 1. Fig. 3, is a section through the machine showing the main operating parts. Fig. 4, is a detail view showing the operating mechanism for the die head in a different position to that shown 40 in Fig. 1. Fig. 5, is a side elevation of the die head.

The blank A, Fig. 3, to be folded is laid flat on the recessed top of the movable folders c, on the folding table b, which is guided 45 and supported in the frame a. The folder carriers are heavy cast plates with beveled tops b', which project above the folders and this arrangement facilitates the operation of the folders and the insertion of the blank A. 50 The folders c, are shown in Fig. 3, moved into their folding position, this movement being effected by centrally pivoted levers r, carrying at their lower ends rollers q, which engage with cams 54, 54', and 56, 55 56', to move the folders at the desired times and in the desired sequence as described in

a co-pending patent application Serial No. 709,261.

The flat blank A, is first cupped by means of dies e, carried by feet f, fixed in movable die heads h h. The feet f are formed on plates g, fixed by bolts i, in the movable die head parts h h. This die head and its method of operation are also described in another co-pending patent application Serial 60 No. 694,243.

The die head h h, is composed of two parts held apart by springs w, (see Fig. 5) fixed on the ends of a centrally pivoted lever x, supported on a standard y. One of the parts h, of the die head has flanges t, through which pass bolts u, as a sliding fit. The bolts u, are rigid with the lower part h, of the die head shown in Fig. 5, this lower part being the front part in Fig. 3. Cast 70 parts v, are rigidly held by the bolts u, being arranged to rest on shoulders on these bolts as shown. A rotatable column z, (of the shape in a transverse plane shown in the plan view Fig. 5) fits between the casing 80 v, and the flange t. In Fig. 5, this column is shown in the position which it occupies when the dies are expanded. When rotated in the direction of the arrows on the right hand end in Fig. 5, the upper die head h, 85 in that figure is caused to approach the lower die head so as to collapse the dies. The rotation of the column z, is effected by means of a cam 5, with which there engages a roller 4, Fig. 2, mounted on an arm 90 z, at the lower end of the rod or column z, which is supported in a sleeve 2, (see Figs. 1 and 2). Each column z, is inclined but is normal or vertical to the plane in which the folding table, formed of the parts b c, and 95 the presser plate d, are arranged. A further movable part of the machine comprises the hot presser plate d, which is resiliently mounted on a pin k, by means of a spring n. The pin k, rests on an arm pivoted at p, and 100 carrying a roller l, engaging on the cam m. The presser plate d, is arranged beneath and parallel to the folders c.

As the shaft s, rotates in Fig. 3, from the position I, under the roller l, to the position 105 II, the blank A, is laid on the folding table, the die head is then moving from the position shown in Fig. 1, along the path shown by the dotted line Y on to the guide or column z. The dies e, are then expanded, 110 that is they are in relative positions indicated in Figs. 3 and 5. The dies e, press the

blank A, on to the presser plate *d*, and thereby pass below the folders *c*. During this action, the folders *c* are of course drawn back from the position shown in Fig. 3. Immediately the dies pass below the folders *c*, these are moved into the positions shown in Fig. 3, and at this point the cam *m*, is rotated as shown in Fig. 3, to a short distance before the point II comes under the roller *l*. In order to prevent the subsequent movement of the dies *e*, from scraping or disturbing the blank A, pin 20, (see Figs. 1 and 4) fixed on the casting *v*, comes to rest on a spring 22, in the recess 21. In this way the die parts *e*, are supported and do not scrape or rub over the surface of the blank. Before the point II, passes the roller *l*, the column *z*, is rotated and the dies *e*, collapse so that they pass between the folded over edges of the blank A. At this point the die head *h* *h*, commences to rise as also the presser plate *d*. From the points II to III the folded blank is pressed and the die head *h* *h*, returned to the position shown in Fig. 1, the folder *c*, being retained during this movement in the position shown in Fig. 3. From the points III to IV, the presser plate *d*, falls a short distance and the folders *c*, are withdrawn. At the point IV, the plate *d*, suddenly falls so as to jerk the folded blank off the table whereupon it slides down and falls into a receptacle suitably placed to receive it.

The above described features are not broadly novel and the description is essential to the proper understanding of the present invention. Hitherto such machines have been arranged with the folding table *b*, *c*, arranged in a horizontal plane, the die head *h*, *h*, has had a straight vertical movement and its operating mechanism has been arranged over the folding table and blank and the presser plate *d*, has not been jerked as at the point IV. It is of the utmost importance in such machines that the collar blanks are properly laid in place in the recessed upper portion of the folders *c*. Experience has shown that with the blank lying horizontally there is considerable skill required in accurately and rapidly placing the blank properly on the folding table. This objection is to a great extent removed by arranging the table inclined as shown, as the blank is naturally laid with its lower edge resting on the side of the lower recess on the top of the folders *c*, that is to say on the left hand edge of the recess or the top of the left hand folder *c* in Fig. 3 and it then automatically falls into its correct position. Then again by inclining the folding table, the folded blank slips off as soon as the hot pressing plate is moved rapidly downward as from the point IV in the cam *m*.

Another difficulty which has been removed by the inclined table consists in the openness of the space directly above the blank and the

absence of any machine parts at this point. These machine parts require to be kept well oiled and the oil frequently fell on to the blank thereby soiling it or rendering it useless. When however, the operating parts are caused to assume a position other than directly over the blank, there is no danger of oil smuts dropping on the blank while the entire work is visible and the table accessible for rapid and accurate insertion of the blank. 70 75

A further feature resides in the jerking of the inclined presser plate so that the blank is automatically released and slips over the smooth polished and inclined surface of the presser plate. 80

A further feature of the construction illustrated resides in the rotatable arrangement of the die head *h* *h*. This enables the machine to be very low and the parts to be lighter so that if desired the machine may be operated by a treadle. By rotating the die head from the position shown in Fig. 3 or 4, to that shown in Fig. 1, the dies *e*, are brought into vertical plane where they may be easily replaced, cleaned, adjusted and inspected when required. If the die head were not so rotated it would require to be raised to a much greater height above the folding table in order to enable access for removing, replacing and adjusting the dies. 85 90 95

Such greater movement of the die head would involve heavier and larger machine parts requiring more power to operate and taking up more space. 100

As described earlier the movable die head *h* *h*, is caused to move in the path Y shown in dotted lines in Fig. 1, and engaging over the inclined standard *z*. The purpose of this curved path is to carry the operating mechanism and the die head itself to a position on one side of the folding table and not directly above it. In the position shown in Fig. 1, the dies *e*, are in a vertical plane being brought thereto by swiveling the die head around its pivotal connection 13. 105 110

The movements of the die head are obtained by the following mechanism. The driving shaft *s*, has a cam or disk 19, on which there is mounted a roller 18. The roller 18, fits into the groove 17, of an oscillating lever 15, pivoted at 16. Pivoted at 14, to one arm of the lever 15, there is a rod 12, having a roller 11, about midway its length. The roller 11, is guided in a curved slot 10, in a casting 9, fixed to the frame of the machine. The upper end of the lever 12, is expanded to form the pivotal bearing for the pin 13, about which the die heads *h* *h*, may swing. The pins 13, are arranged at each side of the die heads as can be seen in Fig. 5, so that the entire mechanism described is duplicated at each side of the machine. The pin 13, is fixed on the plate *v*, carried by the bolts *u*. The part *v*, also carries a pin 7, which is adapted to 115 120 125 130

move in a curved slot 8, formed on the upper end of the rigid plate 9. By virtue of the combined action of the rod 12, guided in the cam slot 10 and the pin 7, traveling in the slot 8, the die head *h*, is caused to move in the path Y and to oscillate from the position shown in Fig. 1, to that shown in Figs. 3 and 4. On the straight down motion, the die head is guided by the rotatable stand-
ards *z*.

In the above description no mention has been made of the end die parts and end folders as these are more fully dealt with in my co-pending application Serial No. 709,261. The mechanism for moving the end folders is shown at 37, the arm 37, being arranged to coöperate with a sliding part 23, with which the end folders move.

claim:

1. In a folding machine in combination, a folding table inclined with respect to a horizontal plane, guiding means normal to the plane of said table, a die and die head movable on said guiding means on to said table, and means for moving said die and die head on the said guiding means normal to and away from the table and then transversely with respect to said normal and free from said guiding means.

2. In a folding machine, in combination, a folding table inclined with respect to a horizontal plane, guiding means normal to the plane of said table and located at the sides thereof, a die and die head movable on said guiding means on to said table and means for moving said die and die head on the said guiding means normal to the table and then transversely with respect to said normal and free from said guiding means.

3. In a folding machine in combination a folding table inclined with respect to a horizontal plane, a die and die head movable in a path normal to said table and then transversely in respect to said normal, a guide arranged normal to said table to coöperate with said die during its movement normal to the table and resilient means located in said guide for supporting said die head when it approaches its lowest position near the table.

4. In combination in a machine for folding collar and like blanks, a machine frame, folding table parts guided in said frame to move in paths inclined to the horizontal, standards supported at the sides of said table and normal thereto, a movable die head engag-
ing over said standards to coöperate with said folding table parts, and means for moving said die head over said standards and then clear and to one side of said standards.

5. In combination in a machine for folding collar and like blanks, a machine frame, folding table parts guided in said frame to move in paths inclined to the horizontal, standards supported at the sides of said table

and normal thereto, a movable die head en-
gaging over said standards to coöperate with said folding table parts, means for moving said die head over said standards and clear and to one side of the same, and means for swiveling said die head after it passes clear of said standards and during its passage to one side thereof.

6. In a folding machine in combination, a folding table inclined in respect to the horizontal, a movable die and die head and means for moving said die and die head in a path starting from said table and normal to same and then transversely in respect to said normal.

7. In a folding machine in combination, a folding table inclined in respect to the horizontal, a movable die and die head, means for moving said die and die head in a path starting from said table and normal to same and then transversely in respect of said normal, a presser plate set to the same inclination as the folding table and located thereunder and means for moving said inclined presser plate normal to and toward said folding table and means for rapidly jerking said inclined presser plate away from and in a path normal to said folding table.

8. In a folding machine in combination, an inclined folding table, a die and die head coöperating with said table, and means for moving said die and die head comprising an oscillating lever, a rod operated by said oscillating lever and connected to said die head, a guide roller on said rod and a curved guide in which said roller moves.

9. In a folding machine in combination, an inclined folding table, a die and die head coöperating with said table and means for moving said die and die head comprising an oscillating lever, a rod operated by said lever, a roller midway in said rod, a curved guide in which said roller works, a pivotal support on the end of said rod and receiving said die head and means for swinging said die head about said support.

10. In a folding machine in combination, an inclined folding table, a die and die head coöperating with said table, means for moving said die and die head comprising an oscillating lever, a rod operated by said lever, a roller midway in said rod, a curved guide in which said roller works, a pivotal support on the end of said rod and receiving said die head, means for swinging said die head about said support comprising an arm on said die head, a pin on said arm and a fixed curved guide receiving said pin.

11. In combination in a folding machine, a frame, folding members inclined to a horizontal plane, carriers therefor guided in said frame, operating parts co-acting with said carriers, a resiliently supported presser plate inclined to a horizontal plane located beneath said folders and a cam having a por-
